(57) **CLAIM**

The ornamental design for a self-adhesive picture hanger, as shown and described.

DESCRIPTION

FIG. 1 is an isometric view of the self-adhesive picture hanger;

FIG. 2 is a front view of the self-adhesive picture hanger of FIG. 1, the rear view being identical;

FIG. 3 is a bottom view of the self-adhesive picture hanger of FIG. 1;

FIG. 4 is a top view of the self-adhesive picture hanger of FIG. 1; and,

FIG. 5 is a right side view of the self-adhesive picture hanger of FIG. 1, the left side view being identical.

The appearance of any portion of the self-adhesive picture hanger between the break lines form no part of the claimed design. The dot-dash broken lines define the bounds of the claimed design and form no part thereof.
